GUN SHROUD

Rufus W. Wilson, Huntingdon, Pa., assignor to Wald Industries Inc., Huntingdon, Pa., a corporation of Pennsylvania

Application May 27, 1952, Serial No. 290,276

3 Claims. (Cl. 299—28.5)

The present invention relates to an attachment for spraying apparatus. More particularly, the present invention relates to a shroud for attachment to a road marking spray gun.

Prior to the instant invention, various devices have been utilized with spraying apparatus for defining traffic lines on roads or pavements. However, these heretofore known devices have generally been undesirable since they do not sharply define the traffic marker and, furthermore, are subject to constant cleaning and repairs. One of these heretofore known marking assemblies consists of a pair of revolving discs which are adjustably mounted with a paint spray gun positioned therebetween. The discs are adapted to direct the spraying material ejected from the spray gun in a pattern on the road in predetermined widths. These disc devices were found to be generally undesirable since paint mist had a tendency to form on the inside surfaces thereof with the result being that in those cases where lines were to be skipped, such as at street or road intersections, the accumulation of mist on the discs dripped off onto the road. It was also found that if the spray gun was shut off, and the discs were moved along the road surface, the accumulated mist deposited thin parallel lines on the road which were not only unsightly but were confusing to the pedestrian and driver. Furthermore, actual practice has proved the discs to be cumbersome inasmuch as they require bulky supporting structure which necessitates complicated mechanical disc retracting mechanism. Moreover, constant maintenance is required to keep the discs clean and, due to the constant contact of the disc peripheries with the road surface, frequent disc replacement is necessary.

Devices similar to the rotatable discs have been used to direct the spray pattern on the road and include such devices as sleds, which are adapted to be positioned on either side of the spray gun. The use of the sleds has also been found to be objectionable for similar reasons discussed above, that is, mist from the spray gun collects on the inner surfaces of the sleds and drips off onto the road when the sleds are lifted therefrom.

Air current ejectors have been used with the most success with spray guns, but even these devices have been found unsatisfactory. The air ejectors operate to direct the spray pattern on the road by ejecting air from nozzles located on either side of the spray gun. However, this operation requires elaborate piping arrangement as well as various adjusting and locking means, which features make the device too complicated for ordinary use.

Still another means in use heretofore with a spray gun for defining a road marking pattern is a device which incorporates wing-like pieces of light sheet metal suspended on wires on either side of the spray nozzle. In this type of device, adjustment of the wing-like pieces has been more or less haphazard and, due to the lack of sufficient enclosures in protecting the spray itself, prevailing winds and air currents generated by passing traffic, have caused undue disturbances in the spray, thereby distorting the line pattern laid on the road.

2

It is an object of the present invention to provide a spraying device which will concentrate the spraying material in even distribution on the road or pavement.

Another object of the present invention is to provide a shroud that is adapted to be secured to a conventional type road marking spray gun and that will direct the spraying material therefrom to the road or pavement in even distribution thereon.

Still another object of the present invention is to provide a paint spray gun shroud that is adapted to prevent paint mist from accumulating on the inner surfaces thereof, thereby preventing unsightly blotches on the street or pavement during the road marking operation.

Still another object of the present invention is to provide a shroud having passages therethrough for admitting air which will act to prevent accumulation of mist along the inner surfaces of the shroud.

Other objects and the nature and advantages of the instant invention will be apparent from the following description taken in conjunction with the accompanying drawings, wherein:

Fig. 1 illustrates one form of the present invention wherein the shroud is shown in vertical section secured to a road marking spray gun;

Fig. 2 is an elevational view of the shroud illustrated in Fig. 1;

Fig. 3 is a plan view of the shroud illustrated in Fig. 2; Fig. 4 is another form of the present invention illustrating in vertical section a modified shroud secured to a road marking spray gun;

Fig. 5 is a plan view of the shroud shown in Fig. 4; and

Fig. 6 is an elevational view of the shroud shown in Fig. 5.

Referring to the drawings, and particularly Fig. 1, one form of the present invention is illustrated secured to a road marking spray gun, which is generally indicated at 10. The road marking spray gun 10 includes an air chamber 12 which houses an air operated needle valve (not shown). An inlet port 14 is connected to air chamber 12 and directs air under pressure to a diaphragm located in the air chamber for operating the needle valve in the conventional manner. Below the air chamber 12 and integrally connected thereto is a barrel 16 which has a paint inlet port 18 and an air inlet port 20 formed therein. The spraying material or paint is introduced into the spray gun through the port 18 and passes through the needle valve (not shown) into the lower portion of the barrel 16 where it is atomized and ejected through a nozzle 22 suitably mounted on the lower portion of the barrel 16. The nozzle 22 is arranged to discharge a fan-shaped spray which is indicated at 24. The nozzle 22 is disposed generally perpendicular to the road indicated at 26 over which the spray gun is carried by suitable apparatus. The fan-shaped pattern 24 is shown forming a stripe "S" on the road 26.

The barrel 16 is adapted to have secured thereto a shroud assembly which includes an internally threaded nut element 28. Formed around a lower portion of the barrel 16 are the threads 30 which receive the nut element 28 in threaded relation.

Referring to Fig. 3, the nut element 28 is shown having formed thereon a series of projections 32 which define therebetween open spaces 34. Referring again to Fig. 1, the shroud assembly is shown including a shroud body 40 which is secured to the nut element 28 in pressed-fit relation. The shroud body 40 is a machined cylindrical tube of steel, bronze, plastic or other suitable material and is formed with a thin wall section and a polished inside surface. The top of the shroud body is machined to provide a pressed fit on the projections 32 and

the bottom is cut away to form oppositely disposed concave sides 42, 44 and oppositely disposed curved lip sections 46, 48. In position, the upper portion of the shroud body 40 closes the outer sides of open spaces 34. The open spaces 34 thereby define passages which are spaced around the top of the shroud and which project into the interior thereof as illustrated in Fig. 1.

In operation, the spray gun shroud body 40 is secured to the spray gun as shown in Fig. 1, and the assembly is suitably positioned on a road spraying apparatus vehicle. The paint is admitted to the barrel 16 and is controllably discharged from the nozzle 22 onto the road surface 26 in the fan-shaped spray pattern 24. The discharge end or lip sections 46, 48 of the shroud body 40 successfully confine the spray pattern to a definitely predetermined width, thereby enabling a clearly defined line to be sprayed on the road surface by the spray gun apparatus. Moreover, the pattern is unaffected by external air currents, since the lip sections 46, 48 act as a baffle protecting the spray pattern from air disturbances caused by high-speed passing traffic. It is understood that the width of the spray pattern "S" may be varied by vertically adjusting the position of the spray gun 10 along with the attached shroud body 40. If a more narrow spray pattern is desired, the spray gun is moved closer to the road 26, while a wider spray pattern may be effected by lifting the spray gun to a higher position with respect to the road 26. However, the shroud body 40 must always be maintained at a suitable distance from the surface of the road 26, thereby effecting a definite spray pattern under all conditions.

As the paint is discharged from the nozzle 22 onto the road surface 26, a fine mist collects along the inner surfaces of the shroud body 40. This mist, if allowed to remain on the inner surfaces of the shroud body 40, would subsequently drip off into the road during the spraying operation and cause unsightly blotches thereon. Moreover, when the spraying operation is stopped momentarily, such as at street intersections, or shut down, the collected spray would drip off the shroud, thereby marring the appearance of the finished marked line. The cut-away sides 42, 44 are limited in surface area and thereby prevent the paint mist emanating from the nozzle 22 from collecting thereon. However, the curved lip sections 46, 48, which define the width of the spray pattern, are continuously subjected to the paint mist and would ordinarily collect a prohibitive amount of mist which would result in the objectionable blotching. The spaces 34, which are formed in the nut element 28, provide convenient openings for the admission of air from the surrounding atmosphere. The incoming air forms an air curtain which moves downwardly along the inner surfaces of the shroud body 40, as shown by the arrows in Fig. 1. It is apparent that the air curtain, as it moves downwardly along the shroud body inner surfaces, carries the mist circulating therearound back into the spray pattern, thereby eliminating the possibility of mist collection and subsequent dripping onto the road.

Referring now to Fig. 4, a modified form of shroud assembly is illustrated, secured to the spray gun 10 described hereinabove. The modified shroud assembly comprises an upper nut 50 having internal threads which are adapted to be threadedly engaged by the threads 30 located on the lower portion of the spray gun barrel 16. Disposed around the upper nut 50 and projecting therethrough are a plurality of passages 52, which are provided for directing atmospheric air to the inner surfaces of shroud body 54. The upper nut 50 is formed with a knurled surface 56 which provides a gripping surface for engaging the nut 50 on the threads 30. Also formed on the nut 50 are threads 58 which engage a knurled lower nut 60. The lower nut 60 is formed with a flange 62 at the lower end thereof which interlocks with a flange 64 integrally formed on the upper end of the shroud body

54. The flange 64 is securely held in place by the nut 60 against the lower end of nut 50, which forms with the shroud body 54 the inner surface of the shroud. The shroud body 54 is cut out at the lower end thereof to 10 form the oppositely disposed concave sections 64, 66 which face in the direction of travel of the spray gun 10. Oppositely disposed curved lower lip sections 68, 70, which limit a spray pattern, indicated at 72, face in a direction at right angle to the direction of travel of the spray gun 10 and are adapted to prevent air currents from disturbing the spray pattern 72 as it is discharged from the nozzle 22 onto road surface 74. As shown in Fig. 4, the spray pattern 72 forms the stripe "S" on the road surface 74.

15 In operation, the paint spray gun 10 is moved along the road surface 74, discharging the spray pattern 72 from the nozzle 22 in a predetermined width determined by the nozzle 22 and lower lip sections 68, 70. Paint mist emanating from the nozzle 22 and circulating along 20 the inner surfaces of the shroud body 54 is forced back into the spray pattern by an air curtain drawn through passages 52 formed in the upper nut 50. It is apparent from the foregoing that the paint mist is successfully prevented from accumulation along the shroud body walls, 25 thereby eliminating any possibility of subsequent drip onto the road surface. It is furthermore apparent that the shroud lower lip sections 68, 70 not only define a definite spray pattern, but prevent any outside air currents from disturbing the pattern as it is discharged from the spray gun nozzle onto the surface of a road or pavement.

30 It will be obvious to those skilled in the art that various changes may be made without departing from the spirit of the invention and, therefore, the invention is 35 not limited to what is shown in the drawings and described in the specification, but only as indicated in the appended claims.

What is claimed is:

1. In an attachment for a road marking spray gun 40 from which a spray pattern is discharged, an upper nut threadedly engaging said spray gun, a lower nut threadedly engaging said upper nut, a cylindrical shroud body interlocked between said upper nut and said lower nut in concentric relation therewith and surrounding the spray 45 gun nozzle, said upper nut having a plurality of passages formed therein extending into the interior of said shroud body, said passages adapted to admit air from the surrounding atmosphere into the interior of said shroud body for preventing the collection of paint mist along 50 the inner surfaces thereof, said shroud body being cut out at the lower portion thereof to define oppositely disposed concave sections and oppositely disposed curved lower lip sections, said lower lip sections adapted to define the width of the spray pattern and to prevent air 55 currents from disturbing said spray pattern.

2. In an attachment for a road marking spray gun 60 from which a spray pattern is discharged, means engaging said spray gun, means engaging said first-named means, a hollow cylindrical member interlockingly secured between said aforesaid means in concentric relation therewith and adapted to be positioned in spaced relation with respect to the road to be marked, said first-named means having passages formed therein extending into the interior of said hollow cylindrical member, said passages admitting air from the surrounding atmosphere into the interior of said member thereby 65 forming an air curtain therein, said air curtain adapted to move downwardly along the inner surfaces of said member and to carry mist emanating from said spray gun back into said spray pattern.

3. In an attachment for a road marking spray gun, means threadedly engaging said spray gun, means threadedly engaging said first-named means, a hollow member secured between said aforesaid means in concentric 70 relation therewith and adapted to be positioned in spaced

relation with respect to the road to be marked, said first-named means having passages formed therein extending into the interior of said hollow member, said passages adapted to transfer air from the atmosphere into the interior of said hollow member for preventing paint mist from accumulating therein.
